UNITED STATES PATENT OFFICE.

EDWIN S. MATTHEWS, OF NEW YORK, N. Y.

HYDRAULIC-MOTOR VALVE.

1,165,430.

Specification of Letters Patent. Patented Dec. 28, 1915.

Application filed August 8, 1914. Serial No. 855,773.

To all whom it may concern:

Be it known that I, EDWIN S. MATTHEWS, a citizen of the United States of America, and a resident of the borough of Manhattan, 5 city, county, and State of New York, have invented certain new and useful Improvements in Hydraulic-Motor Valves, of which the following is a full, clear, and exact description, reference being had to the accompanying drawings, which form a part of this 10 specification.

My present invention relates to hydraulic motor valves, or valves which control the flow of fluid with precision, and particularly to such valves as enable an operator 15 to control the mode of action of a fluid motor.

The objects of this invention are, in general, to secure positiveness, refinement, and a 20 high degree of flexibility in such control, by means of which, within limits, the operator may vary the manner of working of the fluid motor, to which my present improved valve is applied, thus securing improved results in 25 its operation.

A concrete example of the improved control of a fluid motor by use of this invention may be afforded by its application to a 30 hydraulic elevator, where heavy masses are moved at high speeds and where accuracy of stopping, so as to bring the floor of the elevator car level with the landing, is important, and also where loss of time in manipulating the apparatus is inhibited; and this 35 invention is especially suitable for effectively controlling high speed hydraulic plunger elevators.

The main valve of this invention which 40 directly controls the motor to which the device is applied, by permitting the flow of fluid to or from the motor, or by stopping such flow, is in turn controlled by the operator partly by means of a smaller pilot valve which receives motion from both the 45 operator and the main valve causing the main valve to be hydraulically shifted to certain definite positions answering to the positions of the operating handle or mechanism in a way well known in the art and 50 is exemplified in the patent to me No. 465611 granted December 22, 1891.

In the present invention the middle posi-

tions of the operating handle or mechanism bring into action only the aforesaid pilot valve and when the main valve is thus operated by the use of these intermediate positions only, the speed of movement of the main valve is comparatively slow; but the complete operating mechanism for the main valve includes also a booster valve, which 55 received motion from the operator only, and is brought into action only at, or toward, the extreme or end positions of the operating handle or mechanism so that it is entirely under the operator's control, as to the extent to which it shall be employed, if at all, as set forth in detail later; although it cannot be employed without the pilot valve notwithstanding as aforesaid the pilot valve 60 may be employed to its fullest extent without it.

The booster valve is so incorporated into the system that the operator can use it only to quicken the motion of the main valve, and this speeding up of the main valve is 75 in no way automatic but solely at the will of the operator, while the amount of speed attained by elevator car or motor to which this invention is attached, caused by the degree of opening of the main valve, is governed by the pilot valve solely, as is common in the old art.

It will also be seen that the booster valve can be brought into action by the operator only after he has opened the pilot valve so 85 as to give the motor or elevator to which this invention is applied its full speed; so that in making delicate adjustments of car level at landings, by use of the middle positions of the operating mechanism only, the 90 booster valve cannot be employed and violent motion or bounding of the car is thus avoided, and accuracy of adjustment is facilitated.

The size of the pilot valve is made amply 95 sufficient so as to cause it of itself to exercise practically no control of the speed of motion of the main valve, except at the brief and negligible instant when the former is at the point of closing; in order that this 100 control of speed of the main valve may be caused to reside in the effective area of water passages leading to or from the actuating cylinder thereof.

There is also included, in the exemplifying structure herewith shown, an escapement device for the booster valve only; which, while it does not hinder complete reversal at full speed of the elevator car or motor to which this valve is attached, by the operator, checks the bringing into action of the booster valve by him in the case of such reversal and performs that function 10 only.

Other advantages and objects of this invention will be apparent to those skilled in the art, as its construction and mode of operation are hereinafter more fully explained, 15 in detail, in this specification, and its novel features are pointed out in the claims.

The exemplifying structure herein shown, which embodies this invention, is illustrated by the following drawings:—

20 Figure 1 shows this valve attached to a hydraulic plunger elevator exhibiting by dotted lines the respective positions of the operator's controlling device in the car and of the operating bar on the valve, for controlling the pilot and the booster valves. Fig. 2, is a longitudinal or side elevation of this improved valve showing the structure of the main valve, pilot valve, and booster valve in section, and their interconnecting 25 levers, and links, operating bar, and booster valve escapement motion in elevation. Fig. 3 is a front elevation of the apparatus along the line 3, 3 whereby the swinging lever is cut out in order that the escapement apparatus 30 may be clearly shown with the hub carrying the pallets of the escapement being shown in additional section. Fig. 4 is a front end elevation of the valve apparatus showing the swinging lever connecting the main valve, pilot valve, escapement, booster 35 valve and operator's arm together, providing by its various positions for their interconnected motions; this swinging lever being shown partly in section on the line 4, 4. 40 Figs. 5, 6, 7, 8, 9, 10, 11 and 12, are diagrams illustrating various positions of the escapement, the booster valve, and the pilot valve, during the operation of this invention; the operation of a pilot valve controlled main 45 valve, by itself alone, being so well known to those skilled in the art as not to require special additional illustration by drawings.

In these diagrams the main valve has been represented as being opened in and closing 50 from one direction only, for the sake of simplicity; it being obvious that corresponding positions and results from its opening in and closing from the other direction necessarily follow.

60 In Fig. 5 the main valve, pilot valve and booster valve are all shown as being in closed position with the main motor or elevator at rest, and the operating device in central position.

65 Figs. 6, 7, 8 and 9 show various positions

of the apparatus when the booster valve is not brought into action by the operator, although the pilot valve is employed by him to its fullest extent, and in these positions the movement of the operating device is confined to the intermediate positions shown by dotted lines in Fig. 1; although Fig. 8 (representing the instant when the operator has brought his controlling device to the central position to close the main valve from a 70 previously open position and stop the elevator or motor), is equally applicable whether the booster valve has been previously employed in opening the main valve or not.

Figs. 10, 11 and 12 show various positions of the apparatus when the booster valve has been brought into action by the operator, and where his operating device has been swung to the extreme positions away from 80 its center position as also indicated by dotted lines in Fig. 1.

The construction of the exemplifying structure embodying this invention will now be explained more fully in detail, in connection with the drawings above mentioned; and the more obvious features of its operation, such as are easily apparent to those skilled in the art, will be mentioned in this connection; while the peculiar operations of 90 the booster valve and the escapement and their relations to the rest of the apparatus 95 will be considered last in connection with the diagrams therefor.

In order to illustrate a practical application of this invention I have shown in Fig. 1 a hydraulic plunger elevator system (as far as is needful) in which my improved valve is incorporated: The elevator car 1 is attached to and supported by a plunger 2 105 which moves up or down in its cylinder 3, as pressure is applied to it or exhaust is opened thereto respectively, and is held stationary when the fluid is confined therein. Fluid enters or leaves this cylinder by the to and from pipe 4, and this fluid is controlled by the improved valve 5, the direction of fluid flow thereto or therefrom being indicated by arrows, shown in connection with various openings thereof; supply for the plunger 110 elevator cylinder enters at 6 and exhaust therefor leaves at 7; while supply and exhaust for pilot valve 11 of the actuating cylinder 8 by control of which the main valve 5 is properly moved or held stationary, enter and leave by 9 and 10 respectively, the remaining opening at the top of the valve being merely a balancing opening to be connected with the exhaust in case of back pressure thereupon. The supply and 115 discharge of the actuating cylinder 8 of the main valve 5 are directed by a pilot valve 11, and a booster valve 12 (both shown in section in Fig. 2) and these are moved by the operator in the car through the cables 120 130

14 and 15 which are attached to the valve operating bar 13, and proceed therefrom upwardly and respectively over and under the two pairs of wheels forming the well known twin wheel device 16 shown directly under the car 1 and then proceeding farther upwardly they are secured at the top of the elevator shaft, reversed in position as to right and left. These twin wheels are arranged to be rocked by the operator in the car, to a greater or less extent as may be required, by moving his operating lever 17 appropriately; and by thus taking up and letting out loops in the cables 14 and 15 the operating bar 13, is swung into a position corresponding to the position of the operator's lever 17 in the car irrespective of the position of the elevator car or of its state of rest or motion. In the illustration Fig. 1 the operator's lever 17 and the valve operating bar 13 are shown in central position, and the elevator car is stopped with the main, booster and pilot valves all closed. Dotted lines represent some of the various 25 positions of these devices; the aforesaid stopped or stopping position being designated by 18 in the case of each of the devices. The dotted lines 19 represent a position when the pilot valve is fully opened, 30 causing the main valve to be fully opened for ascent of the car at full speed, but without the booster valve having been employed; while position 20 represents the same state of affairs but with the booster valve having 35 been brought into action by the operator and the speed of opening of the main valve quickened thereby and the start of the car expedited. The numerals 21 and 22 represent the corresponding positions for descent 40 of the elevator car. Thus it is seen that the region of pilot valve action alone lies between 19 and 21 and that the united action of pilot and booster valves lies between 19 and 20, and 21 and 22, and the reason for 45 this will be apparent later as the construction of the valve apparatus is described in detail. The twin wheel device is here shown as illustrative merely of a method of transmitting an operator's control to a valve operating bar, for any one of numerous well known methods would answer equally well and this invention is not limited to any particular method of controlling the position of a valve operating bar or equivalent 50 member by an operator.

Passing now to the detailed consideration of the form of the exemplifying valve structure herein shown, it is to be noted that as long as the operator confines his manipulation of his control lever between the points 19 and 21 (Fig. 1) this valve operates simply as one form of a pilot valve controlled main valve, such valves being well known in the art and this invention is not limited

or confined to any particular or specific form of such valve.

In the drawing Fig. 2, 23, 23 are lining tubes forming a seat for the main valve 5 provided with perforated ports 24 and 25 for the supply and discharge fluid respectively supplied through the openings 6 and 7 as already noted while between the tubes is an aperture 26 leading through the opening 4' to the to and from pipe 4 of the main motor or plunger elevator cylinder 3. This 75 valve has an actuating cylinder 27 preferably of an area twice as great as that of the valve seat and this cylinder is provided with the properly fitted and packed actuating piston 28, while the valve parts are respectively 80 provided with suitable pistons 29, for controlling the supply, and 30 for controlling the discharge working within the valve seat. A casing surrounds these parts all being of a generally cylindrical form as also the 85 openings 4', 6 and 7.

In the position shown in Fig. 2 both the supply and discharge are shut off from the aperture 26, and consequently from the main motor or elevator cylinder, in which the 90 fluid is confined, holding this motor stationary.

The actuating and valve pistons are connected by a piston rod 31 and move together and obviously a motion of them to the left 95 (Fig. 2) would connect the main motor or elevator cylinder with the supply while a motion to the right would make connection to the discharge, the elevator ascending in the former case and descending in the latter. The supply pressure exerts a greater force on the actuating piston 28 than it does on the valve piston 29 causing a constant tendency for the pistons to move to the left (Fig. 2) and they will do this whenever 105 the actuating cylinder 27 is opened to the discharge; but when the fluid is confined therein the pistons will remain stationary; while if the actuating cylinder is opened to the supply the actuating piston 28 becomes 110 balanced by the fluid pressure and the unbalanced supply pressure on valve piston 29 moves the pistons to the right (Fig. 2). The main valve 5 is operated in this manner by controlling the supply and discharge of the 115 actuating cylinder 27 by means of the pilot valve 11 which receives motion both from the operator and from the movement of the main valve.

The typical pilot valve 11 is shown as a 120 balanced piston valve of a well known form, 32 being the valve piston and 33 the balancing piston, and in the position represented in Fig. 2 both the supply (entering through opening 9) and the discharge (leaving through opening 10) are cut off from the actuating cylinder 27 and the fluid is confined therein causing the main valve 5

to remain stationary in the stopped position therein shown.

Obviously motion of the pilot valve piston 32 to the right (Fig. 2) will connect the actuating cylinder 27 with the supply and cause the main valve 5 to move also to the right opening it to the discharge and causing the main motor or elevator to descend;— while motion of the pilot valve piston 32 to the left will make corresponding connections of the actuating cylinder 27 to the discharge and of the main valve 5 to the supply causing ascent of the elevator.

The fluid used to actuate the main valve 5 passes to the actuating cylinder 27 through a throttled passage or passages 34 and 35 (either one or both may be employed) their connection with the pilot valve 11 and actuating cylinder 27 being obvious from the drawing (Fig. 2).

The pilot valve piston 32 receives motion from the operator in the car 1 and also from the main valve 5 in such a manner as to cause the main valve 5 to respond to given positions of the operating lever 18 in the car by answering or corresponding positions, by means of the typical mechanism herein shown and now to be described in detail and its operation set forth.

The valve operating bar 13 (Figs. 1, 2, and 3) is journaled in a bearing 36 (carried on the front head 37 of the main valve 5) by means of the shaft 38 from which upwardly projecting rocker arms (see Fig. 3 more particularly) rigidly connected to the operating bar 13 terminate at their tops in bearings 39 in which a rocker pin 40 is journaled. This rocker pin 40 furnishes a pivot for one end of the link 41 and the other end of which is pivoted on the pin 42 carried on the swinging lever 43 which lever is free to swing with reference to its connections on this and also on all other pins with which it is provided and also can swing about the pin 44 carried by the sleeve 45 through which the swinging lever 43 can slip longitudinally being accurately fitted therein.

The pin 46 carried by the top end of the swinging lever 43 swings in the bearings 47 of this swinging lever 43 and is tightly fitted into an eye 48 on the sliding bar 49 which slips longitudinally in the top sleeve 50, being accurately fitted therein, the sliding bar 55 being connected with the piston rod 51 of the pilot valve 11 and moving therewith.

In view of the mechanism described and shown in the drawings the operation of this improved valve when so manipulated by the operator as to cause it to act only as a simple pilot controlled valve will be readily understood by reference to the diagrams Fig. 5, Fig. 6, Fig. 7, and Fig. 8, returning to Fig. 5 which completes the cycle of operations 65 when the valve is opened and closed by the

operator and where the several positions of the apparatus are illustrated.

Fig. 5 shows the apparatus at rest with the main motor or elevator stationary and the operator's lever in its central position and the valve operating bar also in the central position and the main valve closed. Starting from this state of the apparatus Fig. 6 represents the valve apparatus at the instant the operator has thrown his car lever to the point 19 in the car causing the operating bar 13 to assume a corresponding position and the pilot valve (see position of pilot valve piston 32) to be opened so as to place the actuating cylinder 27 open to the discharge through opening 10, but before the main valve has responded to this action of the pilot valve.

Fig. 7 shows the apparatus where the operator's lever and operating bar are still in the same position but after the main valve has responded by opening the cylinder of the main motor to the supply and while the motor is in motion or the elevator is ascending; and in so responding the motion of the main valve has closed the pilot valve bringing it reversely to the position of closure which it occupied before it was manipulated by the operator, and it is easily seen that had the operator opened the pilot valve but partially the main valve would have to make only a shorter movement to close it, and would have been only partly opened answering to the degree of opening the pilot valve and to the extent of movement of the operator's lever. The position in which the main valve has placed the pilot valve now enables the operator by bringing his lever to the center to stop the main motor or elevator; and Fig. 8 represents the apparatus at the instant when the operator has done this bringing the valve operating bar to its central position and before the main valve has responded to this action; and when the pilot valve is thus opened in the opposite direction from the former one it affords the actuating cylinder supply pressure and causes the main valve to respond by closing, thus stopping the main motor or elevator, and at the same time automatically closing the pilot valve and bringing the apparatus once more to the position shown in Fig. 5.

It is obvious that like motion of the operator's lever, and the operating bar of the valve in the corresponding opposite directions would cause similar results attended by the descent of the car or main motor and its stoppage later.

There is also incorporated in the typical structure herein shown and described an additional auxiliary valve which is in no way automatic in its action being capable of movement only by the operator and may be employed by him or not as desired. This 125

is the booster valve shown in side (partly sectional) elevation in Fig. 2 at 12 as having a generally cylindrical form and seat and it is opened and closed by the cylindrical piston 51 which is obviously practically balanced as regards fluid pressure. It is connected with the operating bar 13 positively by the piston rod 52 connecting rod 53 pin 40 and other connections between this pin and the operating bar heretofore described; hence by moving the operating bar 13 sufficiently the operator can open the booster valve which ever way he swings his car lever from the center position, and to any degree required, such action occurring between the points 19 and 20 and also 21 and 22 (see Fig. 1). Inspection of Fig. 2 shows that when closed the booster valve has no effect over the operation of the main valve which performs all its functions of opening, closing or reversing, fully in either direction without its aid. (See also diagrams Figs. 5, 6, 7, 8, 9 and 10.) If the booster valve is opened by the operator it increases the area of the to and from passages to the actuating cylinder by adding thereto a greater or less portion of its port 54 and thus increases the speed of motion of the main valve proportionately to the extent to which it is opened.

The lap of the booster valve is made respectively greater than the combined throw and lap of the pilot valve (see Fig. 2 and the various diagrams) so that its motion between control points 19 and 21 is seen to be mere idle motion and of no effect on the main valve; and when it is opened between control points 19 and 20 or 21 and 22 it is seen that the excess motion of the pilot valve then given to it is mere idle motion as it has no effect on the direction of motion of the main valve or the extent of such motion which latter is limited by projections 54 and 55 and cannot be increased. Hence in this system the actual working control of the pilot valve resides in the divisional region between 19 and 21 only and that of the booster valve in the divisional regions between 19 and 20 or 21 and 22 only, thus affording the operator definite control positions for their employment.

The employment of the booster valve by the operator is illustrated in diagrams Figs. 5, 10, 11, and 8 where Fig. 5 shows the original position of rest for all parts of the apparatus as heretofore described; Fig. 10 showing the opening of the pilot and booster valves to secure the quickest possible opening of the main valve and promptest possible starting of the car at the instant of such opening; and before the main valve has responded to it.

Fig. 11 shows the position of the parts after the main valve has responded to the action of the operator shown in Fig. 10;

while Fig. 8 shows the position of parts at the instant when the operator has moved his device to stop the car and before the main valve has responded thereto; and finally returning to Fig. 5 the position of parts after the main valve has responded to the action of the operator shown in Fig. 8 and all the parts are at rest thus completing the cycle of operations to the original starting point is shown. Only one other use of this fluid controlling valve by an operator remains to be considered namely that of reversal where by one motion of his operating lever (or its equivalent) he not only stops the main motor when in motion but reverses the direction of its motion by shifting the main valve contrawise to its former position. This use is advantageous to an operator in some cases; and inspection of the diagram Fig. 9 shows the position of parts when this fluid controlling valve is completely reversed from full speed of the main motor to full speed in the opposite direction in the usual manner. Such reversal as is seen, does not bring into action the booster valve 51, but an emergency reversal (to be used by the operator in case of impending danger or accident) is provided for in which case the booster valve is brought into action, as illustrated in diagram Fig. 12. This emergency reversal might be accompanied by shock and jar to the machinery and discomfort to the passengers on an elevator and consequently the apparatus is so contrived that the operator must use extra exertion to produce it, thus providing a check against its careless or injudicious use by him. This check is found in the escapement mechanism with which this fluid controlling valve is provided, which will now be described.

The stationary stud 56 projecting laterally and horizontally is carried on the front head 37 by means of a bracket integral therewith, and on this stud swings the guard 57 of the escapement its lower surface being an arc of a circle concentric with the stud and this guard receives motion from the stud 58 fixed thereto. The stud 58 receives motion from the link 59 through the pin 60 carried by the swinging lever 43 (see Figs. 2, 3 and 4 and the various diagrams). Co-operating with this guard 57 are the pallets 61 of the escapement, projecting upwardly from the lower arms of an inverted T shaped member 63 which can swing on the pin 40 whenever the force of either leaf spring 62 is overcome; being kept in a normal position (unswung about the stud 40) by the combined action of these two leaf springs 62 and when kept in this position they swing normally about the center of the operating bar shaft 38. Although an excess pressure applied to either of these pallets will cause them to yield, overcoming the

force of spring 62, and swing about the center 40.

Inspection of Fig. 2 and the diagram Fig. 5 shows that when the operating bar 13 is 5 swung to start the apparatus the pallets 61 would be brought into contact with the guard 57 were it not that the swinging of the operating bar 13 causes the guard 57 to be moved out of the way so as to escape the 10 pallets 61 (see Figs. 6, 10 and other diagrams). This enables the operator to bring the booster valve freely into action, if he so desires, although the region of its control by the operator lies beyond the point where 15 the pallets 61 are brought into contact with the produced arc of the guard 57, while up to that point the full control of the pilot valve known to the old art, both in stopping, starting and reversing the main valve 20 from full speed in one direction to that in the other (as exemplified in my Patent No. 465611) is fully afforded while the pallets 61 do not cut the arc of the guard 57; this region being always free from all restriction. 25 When however the operator reverses the apparatus from full speed in one direction to that in the other direction the escapement offers a resistance to his employment of the booster valve, thus restricting the operator's control for in such case the pallets 30 of the escapement 61 are brought into contact with arc of the guard 57 (see diagram, Fig. 9); but the application of excess force on the part of the operator will cause the 35 pallets 61 to yield against the force of the spring 62 as already described and permit him to use the booster valve for emergency reversal if necessary. (See diagram Fig. 12). Obviously this resistance to the operator's use of the emergency reversal (which 40 is believed to be an entirely new feature in the valve art) may be made as great as desired by the degree of stiffness of the springs 62 employed or their equivalent; or the operator may be deprived of the emergency reversal entirely by making the pallets 61 solidly connected and yet the other benefits of this invention be fully utilized.

Many variations in the construction of 50 details and the location and relative arrangement of parts would readily suggest themselves to those skilled in the art to which this invention relates and still fall within the spirit and scope of my invention; 55 hence I do not desire to be limited to the exact construction herein set forth; but having explained the principles of my invention, and a preferred form of apparatus embodying it, and—

60 Having described the function, purpose and mode of operation of such apparatus what I claim as new and of my own invention, and desire to secure by Letters Patent of the United States is,—

1. In an elevator, the combination with 65 the car, of motor means therefor, a controlling device for said motor comprising a device to effect acceleration, and an operator's controlling means for said motor controlling device arranged to move in divisional 70 regions one arranged for controlling the direction of motion and speed of said motor, and the other for controlling its acceleration.

2. The combination with a fluid motor of 75 a pilot valve operated main valve for controlling said motor, and an operator moved booster valve for increasing the acceleration of the fluid motor.

3. The combination of a pilot valve operated fluid controlling valve and a booster 80 valve movable only by the operator for increasing the speed of movement of said fluid controlling valve.

4. The combination with a pilot valve operated fluid controlling valve, of a booster 85 valve movable only by the operator for varying the speed of movement of said fluid controlling valve.

5. The combination with a three-way fluid 90 controlling valve of means for opening and closing said valve in either direction and hand operated means for increasing the speed of movement of said fluid controlling valve.

6. The combination with a three-way fluid 95 controlling valve of means for opening and closing said valve in either direction, and hand operated means for varying the speed of movement of said controlling valve.

7. The combination with a pilot valve operated fluid controlling valve of a booster-valve movable only by the operator for increasing the speed of movement of said fluid controlling valve more or less at the 100 operator's will.

8. The combination with a pilot valve operated fluid controlling valve of a booster-valve movable only by the operator for varying the speed of movement of said fluid controlling valve more or less at the operator's 110 will.

9. The combination with a three-way controlling valve of means for opening and closing said valve in either direction and hand operated means for increasing the 115 speed of movement of said fluid controlling valve more or less at the operator's will.

10. The combination with a three-way controlling valve of means for opening and closing said valve in either direction and hand operated means for varying the speed of movement of said controlling valve more or less at the operator's will.

11. The combination with a main valve 125 for controlling the passage of fluid, of means for opening and closing said valve and hand operated means for increasing the speed of movement of said main valve.

12. The combination with a main valve for controlling the passage of fluid, of means for opening and closing said valve and hand operated means for varying the speed of movement of said main valve. 65
13. The combination with a main valve for controlling the passage of fluid of means for opening and closing said valve and hand operated means for increasing the speed of movement of said main valve more or less at the operator's will. 70
14. The combination with a main valve for controlling the passage of fluid of means for opening and closing said valve, and hand operated means for varying the speed of movement of said main valve more or less at the operator's will. 75
15. The combination with a fluid motor of a pilot valve operated main valve for controlling said motor, and an operator moved booster valve for increasing the acceleration of the fluid motor more or less at the operator's will. 80
16. The combination with a pilot valve operated fluid controlling valve of an operator moved booster valve constructed and arranged to be opened by said operator only after the pilot valve has been opened. 85
17. The combination with a pilot valve operated fluid controlling valve of an operator moved booster valve constructed and arranged to be opened by said operator only by movement of the operating device away from its central position. 90
18. The combination with a pilot valve operated fluid controlling valve of an operator moved booster valve constructed and arranged to be necessarily closed when the operating device is at or near its central position, and opened when the operating device is moved therefrom. 95
19. The combination with a pilot valve operated fluid controlling valve of an operator moved booster valve constructed and arranged to be opened only by movement of the operating device to or near extreme positions away from its central position. 100
20. The combination with a pilot valve operated fluid controlling valve of an operator moved booster valve constructed and arranged to be opened by said operator to a greater or less degree. 105
21. The combination with a main valve for controlling the passage of fluid, of means for moving said main valve, of a pilot valve arranged to control the direction and extent of said motion and an operator moved booster valve constructed and arranged with a lap respectively greater than that of the pilot valve. 110
22. The combination with a main valve for controlling the passage of fluid, of fluid motor means for opening and closing said main valve, secondary valve mechanism for controlling said fluid motor means, and supplementary valve mechanism adjustable by the operator for increasing the speed of motion of the main valve. 115
23. The combination with a main valve for controlling the passage of fluid, of fluid motor means for opening and closing said main valve, secondary valve mechanism for controlling said fluid motor means, and supplementary valve mechanism adjustable by the operator for increasing the speed of opening of the main valve. 120
24. The combination of a pilot valve operated fluid controlling valve and a booster valve movable only by the operator constructed and arranged to increase the speed of opening of said fluid controlling valve. 125
25. The combination of a pilot valve operated fluid controlling valve and a booster valve movable only by the operator constructed and arranged to increase the speed of opening of said fluid controlling valve more or less to the degree to which it is employed. 130
26. The combination of a pilot valve operated fluid controlling valve, and a booster valve adjustable by the operator, constructed and arranged to increase the speed of opening of said fluid controlling valve. 135
27. The combination of a motor moved fluid controlling valve and a booster valve adjustable by the operator for increasing the speed of movement of said fluid controlling valve. 140
28. The combination of a motor moved fluid controlling valve and a booster valve adjustable by the operator for varying the speed of movement of said fluid controlling valve. 145
29. The combination of a motor moved fluid controlling valve and a booster valve adjustable by the operator for varying the speed of opening of said fluid controlling valve. 150
30. The combination with a main valve for controlling the passage of fluid, of fluid motor means for opening and closing said main valve, secondary valve mechanism for controlling said fluid motor means, and supplementary valve mechanism adjustable by the operator for varying the speed of motion of the main valve. 155
31. The combination with a main valve for controlling the passage of fluid, of fluid motor means for opening and closing said main valve, secondary valve mechanism for controlling said fluid motor means and supplementary valve mechanism adjustable by the operator for varying the speed of opening of the main valve. 160
32. The device for varying the speed of opening and closing a valve, comprising an actuating cylinder having in connection therewith a passage for fluid flow of deter-

mined area, and a supplementary passage adjustable by the operator.

33. The device for varying the speed of opening a valve comprising an actuating cylinder having in connection therewith a passage for fluid flow of determined area and a supplementary passage adjustable by the operator.

34. The device for varying the speed of opening a valve comprising an actuating cylinder having in connection therewith a passage for fluid flow of determined area always open, and a supplementary passage adjustable by the operator for increasing the area for fluid flow.

35. The device for varying the speed of opening and closing a valve comprising an actuating cylinder having in connection therewith a passage for fluid flow of determined area, and a supplementary passage adjustable by the operator for increasing the area for fluid flow.

36. The device for varying the rate of movement of a valve comprising an actuating cylinder having in connection therewith a passage for fluid flow of determined area, and a supplementary passage adjustable by the operator for varying the area for fluid flow.

37. The combination with a main three-way fluid controlling valve, of means for opening and closing said valve, in either direction, and hand operated means for offering to the force applied to move said valve a greater or less resistance substantially as described.

38. The combination with a main three-way fluid controlling valve of means for opening and closing said valve in either direction, and hand operated means for offering to the force applied to open and close said valve a resistance different as between the opening and closing movements of said valve.

39. The combination with a main three-way fluid controlling valve, a pilot valve, operating means for said fluid controlling valve, whereby it may be caused to move fully throughout its full extent of motion in either direction, and accelerating means constructed and arranged to be operative only after the said pilot valve has been positioned so as to cause full opening of the said fluid controlling valve.

40. The combination with a main three-way valve of operating and accelerating means for the said valve constructed and arranged to be used separately or together dependent upon the position of the operating handle.

41. The combination with a main three-way valve, of motive means for moving said valve, means for controlling said motive means, and hand operated regulating means

comprising a fluid passage or passages and valve mechanism therefor whereby the rate of movement of the main valve in both directions may be regulated.

42. The combination with a fluid motor of a pilot valve operated fluid controlling valve, an operator-moved booster valve, and an escapement governing the employment of the booster valve.

43. A pilot valve operated fluid controlling valve provided with a booster valve and an escapement substantially as described.

44. The combination of a pilot valve operated fluid controlling valve with a booster valve, an operating bar arranged to move both the booster and pilot valves and provided with a projection and a guard adapted and arranged to be automatically moved into the path of said projection whereby the opening of the booster valve is prevented.

45. The combination of a pilot valve operated fluid controlling valve with a booster valve, an operating bar arranged to move both the booster and pilot valves and provided with a projection, and a guard adapted and arranged to be automatically moved into the path of said projection whereby the opening of the booster valve is restricted.

46. The combination with a fluid controlling valve of a pilot valve, a booster valve, an operating bar for opening and closing said pilot and booster valves, and an escapement adapted and arranged to prevent the opening of the booster valve upon reversal of the said fluid controlling valve.

47. The combination with a fluid controlling valve of a pilot valve, a booster valve, an operating bar for opening and closing said pilot and booster valves, and an escapement adapted and arranged to allow unrestricted action of the pilot valve and to prevent opening of the booster valve upon reversal of the said fluid controlling valve.

48. The combination with a fluid controlling valve of a pilot valve, a booster valve, an operating bar for opening and closing said pilot and booster valves, and an escapement adapted and arranged to allow unrestricted action of the pilot valve and to restrict the opening of the booster valve upon reversal of the said fluid controlling valve.

49. In an elevator, the combination with the car, of motor means therefor, a controlling device for said motor comprising a device to effect acceleration, an operator's controlling means for said motor controlling device arranged to move in divisional regions, one arranged for controlling the direction of motion and speed of said motor, and the others for controlling its acceleration and an escapement governing the operator's use of the acceleration regions aforesaid.

50. In an elevator, the combination with the car, of motor means therefor, a controlling device for said motor comprising a device to effect acceleration, an operator's controlling means for said motor controlling device, arranged to move in divisional regions, one arranged for unrestrictedly controlling the direction of motion and speed of said motor and the other adapted and arranged for restrictedly controlling its change of speed.
